UNITED STATES PATENT OFFICE.

WILLIAM A. MORTON, OF LOS ANGELES, CALIFORNIA.

INSULATOR.

No. 866,596.

Specification of Letters Patent.

Patented Sept. 17, 1907.

Application filed November 6, 1906. Serial No. 342,297.

To all whom it may concern:

Be it known that I, WILLIAM A. MORTON, a citizen of the United States, residing at Los Angeles, in the county of Los Angeles, State of California, have invented 5 a new and useful Insulator, of which the following is a specification.

This invention relates to insulators for electric wires, such as telephone, telegraph, electric light wires, etc., and its main object is to provide means whereby the 10 wire may be readily secured to the insulator without the use of the usual wire binder.

In the accompanying drawings:—Figure 1 is a vertical section of the insulator, transverse to the wire. Fig. 2 is a side elevation, partly in section. Fig. 3 is 15 a side view of a different form of the invention.

Referring to Figs. 1 and 2, 1 designates the body of the insulator, of glass or other insulating material and having a screw threaded hole 2 or other means for attachment to a support. The top of the insulator body 20 may be rounded as shown. In the side of the body is a slot 3 extending inwardly to a cylindrical passage 4, provided with screw grooves 5. A cylindrical retaining member 6 fits in said passage and is provided with a screw flange 7 to engage said groove, the member 6 being screwed into place in the passage for turning it. In one side of this member 6 is a longitudinal groove 8 parallel to the axis of the screw and to the slot 3. Member 6 is provided on one end with means for turn-

ing it for example a rib 9 be gripped by a wrench or pincers.

In using the device the member 6 is turned to register with groove 3, the wire is inserted through the slot 3 into the groove 8, and the member 6 is then turned, for example to position where the groove 8 is at the bottom or to the position where the said groove is at the 35 side away from slot 3, as shown in dotted lines in Fig. 1. In either of such positions the friction of the screw flange and groove 8, 7, on one another will be such as to prevent turning back of the member 6 by pressure from the wire, the pitch of these screw parts being sufficiently steep to resist such turning.

The slot 3 and passage 5 may be at the top of the insulator as shown in Fig. 3.

What I claim is:—

1. An insulator comprising a body having a cylindrical screw threaded passage and a slot extending thereinto, and a cylindrical screw threaded member in said passage and having a groove extending parallel to the slot in the insulator body.

2. An insulator comprising a body having a screw threaded passage, and a slot extending thereinto, and a screw threaded member engaging in said passage, and having a longitudinal groove.

In testimony whereof, I have hereunto set my hand at Los Angeles California this 24th day of October 1906.

WILLIAM A. MORTON.

In presence of—

ARTHUR P. KNIGHT,
FRANK L. A. GRAHAM.
